UNITED STATES PATENT OFFICE.

WILLIAM HUMANS, OF CAMBRIDGE, MASSACHUSETTS, ASSIGNOR TO THE AMERICAN MAGNETIC ELECTRIC COMPANY, OF JERSEY CITY, NEW JERSEY.

MAGNETO-ELECTRIC MACHINE.

SPECIFICATION forming part of Letters Patent No. 388,877, dated September 4, 1888.

Application filed July 23, 1885. Serial No. 172,436. (No model.)

To all whom it may concern:

Be it known that I, WILLIAM HUMANS, of Cambridge, in the county of Middlesex and State of Massachusetts, have invented a new and useful Magneto-Electric Machine, of which the following is a specification, reference being had to the accompanying drawings, making a part hereof, in which—

Figure 1 is a cross-section on line xx of Fig. 2, which is a plan, and of Fig. 3, which is a bottom plan with the bottom removed, illustrating one form of my machine. Fig. 4 is a plan illustrating the top cover, G. Fig. 5 is a detail showing one-half of the cover G. Fig. 6 is a detail showing the handle, its sleeve, and one of the gears in side elevation. Fig. 7 illustrates one part of the washer which surrounds the sleeve of the handle. Fig. 8 is a diagram for illustration. Fig. 9 is a section, and Fig. 10 a plan of a modified form of my apparatus.

My invention is mainly a case which is composed of a series of permanent magnets arranged to form a permanent compound magnet, in combination with an armature arranged within the case, and suitable means for revolving the armature and connecting its coil with the line-wire, my device being a substitute for both the ordinary push-buttons and the battery now employed with them, for bells or other signals are operated by my device without the expense and care of batteries.

The case A of my device is composed of a number of permanent magnets, 1, 2, &c., held together, like pole to like pole, (and this, although of my invention, is not here described or claimed, as it forms the subject-matter of an application for patent filed by me, Serial No. 172,432.) Within this case are two pole-pieces, a a , which are shown as held in place by means of the screws a' , which pass through lugs on each magnet, and also through the pole-pieces and nuts a^2 . The ends of these screws a' project sufficiently to receive the nuts a^3 , by which the bottom a^4 is held in place, as shown in Fig. 9, in which B is a hoop and G a cover, all described in my application for patent above referred to.

The armature B' is of the Siemens type, but is also new in its construction, but is not

here claimed, as it forms the subject of an application filed by me, Serial No. 172,433, the end pieces, b b , being recessed into the armature and held by cross-rods b' , and the cross-pieces b^2 b^3 serving to support the journals of the armature and being held together by the cross-rods b^4 , both these features being described and claimed in the applications referred to.

The bridge b^2 has upon it a tubular post, b^5 , which is the box or bearing for one journal of the armature, as clearly shown in Fig. 9. This tubular post has a sleeve, b^6 , upon it to which the gear d is fast, and to which, also, the shoe d' of the crank D is fast. The gear d meshes with pinion d^2 , which is fast to gear d^3 , which latter gear meshes with the pinion i on the armature-shaft. By this feature of my invention I am enabled to make the axis of the crank in line with the axis of the armature and yet cause the armature to revolve many times for each revolution of the crank.

One end of the coil on the armature is in electric connection with the armature and the other end with the electrode f , and the electrode f is held out of contact with the electrode f' by the spring f^2 , but of course is electrically insulated from the spring f^2 . The line l is kept closed and the magneto machine out of line by making the electrode f' in the form of a spring with a pressure against the electrode f^3 ; but when the armature is revolved to induce currents in the line the pressure of the fingers on the crank D moves the armature so as to bring the electrode f in contact with f' , and also to break contact between f' and f^3 , thus throwing the currents onto line by means of the branch l' .

In the diagram, Fig. 8, I have shown two generators and two signals in one line in order to illustrate clearly this feature of my invention, which consists in the combination of the armature-coil with the line-wire by means of an electrode fast to the armature, but insulated from it, and in electric connection with the armature-coil, and a second electrode connected to line but out of contact with the insulated electrode on the armature until the armature is moved endwise against the force

of a spring, this spring acting to break contact between the armature and line-electrodes as soon as the armature is left free.

I have shown the crank D hinged to the shoe d' and bearing upon a spindle fast to the upper journal of the armature, all so arranged that when the fingers are applied to the crank-handle q' the armature will be moved endwise, and thereby the armature-coil 10 to be connected to line by means of the electrodes $f'f''$, as above described. The shape of the handle shown in Fig. 1 is especially devised for this purpose, for it is practically impossible when the handle is shaped as shown 15 to revolve the armature without pressing it in and thereby forcing electrode f against electrode f' , and also forcing electrode f' away from electrode f'' . The stop d' prevents the crank D from moving too far away from shoe d' .

In Fig. 1 I have shown my apparatus constructed to be inserted in a recess in the wall of the room, or the like, by making a flange, g , around the top of the magnetic box or case, this flange being preferably in two parts integral with the upper magnets, 1 and 2, as shown; but it may of course be made separate and properly secured to the magnetic box or case. This is an important feature of my invention, the novelty of which resides in a permanent 25 magnet whose component magnets form a magnetic box or case, and which has a flange or its equivalent around one end, whereby it may be fitted into and held in a recess in the wall with its exposed flanged end nearly flush with the wall. This form of my apparatus is especially desirable where buildings are to be permanently fitted up with electric signaling apparatus, for the permanent magnet has heretofore been the bulkiest and most unsightly part of the magneto-instrument, while by my construction the magnet is mainly or altogether out of sight.

Another feature of my invention consists in recessing the front piece of the apparatus, as shown in Figs. 1 and 9, the walls of the recess serving as a guard to prevent accidental injury to the crank. I have shown the crank

in a recess in the outer magnets, 1 2, but it will be clear, as before, that the magnets 1 2 may be replaced by a non-magnetic mold-board.

What I claim as my invention is—

1. In combination with the armature-coil, a magneto-machine, and the line, an electrode on but insulated from the armature, a second electrode connected with the line, and a spring by which the two electrodes are held out of contact until the armature is moved against the force of that spring, substantially as described.

2. In combination, the armature B' , electrodes $f'f''$, spring f^2 , and electrode f^3 , whereby the armature-coil is out of line and the line is unbroken until the armature is moved against the spring, when the armature-coil is brought 65 into line, all substantially as described.

3. In a magneto-machine, the crank D, in combination with shoe d' and armature B' , whereby when the crank is turned the armature is moved endwise as well as revolved, 70 substantially as and for the purpose specified.

4. In a magneto-machine in which the circuit is closed by manipulation of the crank or handle of the machine, a knob which is smallest at the outer end and largest at the inner end, whereby when the fingers are applied to turn the crank the knob is also moved toward the machine.

5. In a magneto machine, in combination, the crank, the armature, gear d , pinion d^2 , gear 80 d^3 , and the armature pinion, the axis of the gear d and of the armature-pinion being coincident with the axis of the crank and armature, all substantially as described.

6. A magneto-machine whose body is formed 85 of magnets arranged together, substantially as shown, closed at the ends by covers, and with the armature and pole-pieces within the case so formed, all substantially as described.

WILLIAM HUMANS.
